PAIR OF SUNGLASSES

Anthony Shindler, Brookline, Mass., assignor to American Optical Company, Southbridge, Mass., a voluntary association of Massachusetts

Filed June 14, 1965, Ser. No. 85,731

Term of patent 7 years

(Cl. D57—1)

FIG. 1 is a top plan view of a pair of sunglasses embodying my new design;

FIG. 2 is a front elevational view of the sunglasses shown in FIG. 1;

FIG. 3 is a rear elevational view thereof; and

FIG. 4 is a side elevational view thereof.

The temples have been omitted in FIG. 3 for convenience of illustration.

I claim:

The ornamental design for a pair of sunglasses, substantially as shown and described.
